UNITED STATES PATENT OFFICE

FREDERICK C. OVERBURY, OF NEW YORK, N. Y., ASSIGNOR TO, FLINTKOTE MANUFACTURING COMPANY, OF RUTHERFORD, NEW JERSEY, A CORPORATION OF NEW JERSEY.

FLEXIBLE ROOFING.

1,198,653.

Specification of Letters Patent. Patented Sept. 19, 1916.

Application filed February 8, 1912. Serial No. 676,417.

To all whom it may concern:

Be it known that I, FREDERICK C. OVERBURY, a citizen of the United States, and resident of New York, in the county of New York and State of New York, have invented certain new and useful Improvements in Flexible Roofing, of which the following is a specification.

This invention relates to roof coverings, which are made of strips of flexible sheet material cut in such manner as to simulate shingles. The roofing strip used in carrying out this invention is similar to that shown in U. S. Letters Patent No. 908,125, granted to me Dec. 29, 1908.

The improvement to which the present invention relates lies in the manner of laying and securing the roofing strips rather than in the structure of the strips themselves. The sheet material of which such strips are made, is thinner than the exposed portions of wooden shingles, and because of the difference in thickness, the roofing does not carry out the simulation of shingles to the desired degree.

The improvement in securing the lower ends of the tabs according to the present invention, consists in driving a fastener through both layers or thicknesses of each of the doubled portions, so that the outer layer will be engaged and held directly by the head of the fastener.

Of the accompanying drawings which illustrate this invention, Figure 1 represents an elevation of a blank of sheet material of which the roofing strips are made. Fig. 2 represents an elevation of a short length of a roofing strip made from the blank shown in Fig. 1. Fig. 3 represents an elevation similar to Fig. 2, showing the lower edges of the tabs turned under to give double thickness at the lower ends of the tabs. Fig. 4 represents an elevation showing the preferred arrangement of succeeding courses of roofing strips. Fig. 5 represents a section in a plane indicated by a line 5—5 of Fig. 4, showing one method of securing the roofing to a foundation.

Similar reference characters indicate the same parts wherever they occur.

A blank of suitable sheet material for roofing purposes is indicated in Fig. 1 at 10. This blank is to all intents and purposes similar to the one shown in the above-mentioned Patent No. 908,125, with the excep-

tion of the scored lines which are provided for facilitating the folding as hereinafter explained. This blank as shown is intended to be divided into two pieces, of which each piece will constitute a roofing strip. The line of division is represented by the dotted line 11, which extends longitudinally and which is substantially mid-way between the side edges. The blank is provided with a longitudinal series of slots 12, which extend transversely and which are disposed so that each extends an equal distance in both directions from the line 11 of division. Both ends of each slot are closed, thus leaving continuous marginal portions 13. The blank, may, if desired, be scored on lines represented by dotted lines 14, 14, which are parallel to the line of division and disposed on opposite sides thereof. Lines 14, 14 represent the lines on which the tabs are creased or folded as hereinafter explained.

When the blank is divided on line 11, two roofing strips of identical configuration are provided. One of such roofing strips is indicated in Fig. 2 by reference character 15. The line of division, intersecting the slots 12, provides shingle-like tabs 16. If the blank has been previously scored, as indicated at 14, each tab will be scored, so that its lower edge may be readily folded under as shown by Fig. 3, the portion so folded being indicated at 17. In this way the thickness of the lower edge of each tab is doubled, and the simulation of a shingle is greatly increased.

When the roofing strips are laid upon a foundation, they are preferably arranged in the relation shown by Fig. 4, which relation carries out the general scheme of shingling. When laying the roofing strips, work is begun by securing a strip or course of strips to the bottom of the foundation, and the work progresses upwardly, in accordance with the usual manner of shingling. A roofing foundation is indicated at 18 in Fig. 5. As each roofing strip is laid upon the foundation, it is secured thereto by nails 19, which are driven through the upper marginal portion of each strip. When the entire foundation has been covered by roofing strips attached by nails 19, the individual tabs 16 are secured as hereafter explained, so as to prevent a wind from lifting them. All of the nails 19 which are used to secure one strip, are covered and

protected by the strip next above, so that they are all concealed and so that moisture cannot work along them to the foundation 18.

- 5 The means shown by Fig. 5 for fastening down the lower ends of the tabs 16, comprises fasteners 20, whose inner ends are bifurcated and clenched. Each fastener 20 has a head at its outer end and is driven 10 from the exterior and caused to pass through both layers of the doubled portion of a tab 16, and through the upper marginal portion of the roofing strip next below. The inner end of the fastener is clenched against 15 the under side of the strip next below and is separated from the foundation 18 by the second strip below. Wherever moisture seeps through the layers which are penetrated by the fastener, it will be carried off 20 by the layer next the foundation so that it will not reach the foundation. When all the tabs are secured in this manner, the whole number of roofing strips becomes a 25 roofing unit, each strip thereof being secured directly to the foundation and also secured directly to the roofing strips above and below it. The means employed and the method followed for turning back and clenching the points of the fasteners 20 do 30 not form any part of the present invention. It may be well, however, to state briefly how the fasteners are clenched. When the desired number of strips have been laid upon the roof and secured thereto by the nails 35 19, a metal plate is inserted temporarily

under the second strip from the top so that it will lie between the second and third strips. It is placed in position where it will be struck by a fastener driven through the doubled lower end of a tab of the top strip. 40 When the fastener is driven, its points are turned back and clenched by their contact with the aforesaid metal plate. The metal plate is removed after each fastener has been driven and clenched, and is placed in 45 similar relation to each tab upon the roof, all of the fasteners 23 being driven and clenched individually.

I claim:

The combination with a supporting surface, of a series of strips of flexible non-metallic material arranged horizontally thereon, so that each strip overlaps two adjacent lower strips, the exposed edge of each sheet having a series of tabs resembling 55 shingles, the free ends of said tabs being folded under to form thickened edges, fasteners securing the upper overlapped edge of each strip directly to the supporting structure, and fasteners securing the lower 60 edge of each tab only to the body of the strip directly overlapped thereby, and located over the upper portion of the lowermost strip.

In testimony whereof I have affixed my 65 signature in presence of two witnesses.

FREDERICK C. OVERBURY.
